SHARPENING ATTACHMENT FOR CLOTH-CUTTING MACHINES

Albert P. Komow, New York, N. Y.

Application February 1, 1939, Serial No. 253,989

3 Claims. (Cl. 51—249)

My invention relates to a new and improved sharpening attachment for cloth-cutting machines.

One of the objects of the invention is to provide a simple attachment which can be readily applied to, and which can be removed from, a cloth-cutting machine of the type which has a vertical straight-edge reciprocating knife.

Another object of the invention is to provide a device which will come into operative contact with suitable guide means, before the grinding means contact with the knife.

Another object is to provide an extremely simple device which will be very reliable and durable, and which can be made at low cost.

Other objects of my invention will be set forth in the following description and drawings which illustrate preferred embodiments thereof, it being understood that the above statement of the objects of my invention is intended generally to explain the same without limiting it in any manner.

Fig. 1 is a side elevation, showing the improved device applied to a conventional cloth-cutting machine which has a vertically reciprocating knife which has a straight-edge. Part of the representation of the attachment has been broken away, in order to illustrate certain parts more clearly.

Fig. 1A is a partial top plan view of one of the arms of the device, showing the lateral extension thereof.

Fig. 1B is a view similar to Fig. 1A, showing a portion of the second arm of the device and the lateral extension thereof.

Fig. 1C is a top plan view of the supplemental block which comprises one of the jaws of the device.

Fig. 2 is a top plan view of Fig. 1.

Fig. 3 is a sectional view on the line 3—3 of Fig. 2.

Fig. 4 is a top plan view of the attachment in the open or inoperative position.

Fig. 5 is a partial top plan view, showing how the device is operatively mounted on a suitable guide, while the grinding means are spaced from the knife.

Figs. 6 and 7 are respectively sectional views on the lines 6—6 and 7—7 of Fig. 2.

The conventional cloth-cutting machine to which the device is applied, has the usual knife 1, and a holder 2 therefor. The drawings do not show the mechanism for reciprocating said knife 1 vertically, in a direction parallel to its vertical straight edge, as such mechanism is well known.

A vertical rod 3 is suitably connected to the frame of the machine. The device comprises a first arm 4a, and a second arm 4. Said arms 4a and 4 respectively have handhold portions 5a and 5. A compression spring 23 is suitably located between said arms 4a and 4, so as to hold the parts normally in the position shown in Fig. 2. As shown in Figs. 1A and 2, the first arm 4a is provided with an integral projection 6, which extends inwardly and laterally. The second arm 4 is provided with an integral inwardly and laterally extending projection 11a, which is integral with an upstanding block 11, which is shaped so as to provide a jaw 12. A supplemental block 8 is provided with a second jaw 9. The block 8 is located at the top of the block 11. A pivot pin 18 turnably connects the members 6, 11 and 8. This pivot pin 18 has an enlarged head at one end thereof. The other end of said pivot pin 18 is externally threaded and said end of the pin 18 is screwed into the tapped bore 6d of the member 6. Said pin also passes through the bore 11d of the member 11. A nut 19 holds the pivot pin 18 to the member 6.

As shown in Fig. 2, a spring 20, which is preferably a blade spring, has one end thereof connected to the arm 4a by means of a screw 22. Said spring 20 has an upstanding portion which is connected by means of a screw 21 to the upstanding wall of the member 8. The member 8 is provided with an extension 10 which has a recessed top wall, so as to provide a convenient rest for the thumb of the operator, as shown in broken lines in Fig. 1. The arm 4a is provided with an angular extension 4b, to which a bracket 13 is connected by a screw 26. Said bracket 13 has an arm 13a. An emery wheel 17 is turnably mounted upon a suitable stud shaft, which is connected to the arm 13a. A companion emery wheel 17a is turnably connected to the arm 14a of a bracket 14. Said bracket 14 is connected to the angular extension 4c of the arm 4, by means of a screw 27. The emery wheels 17 and 17a are identical and they are connected in the same manner to the respective arms 13a and 14a. Hence the disclosure of Fig. 3 applies to both of said wheels. As shown in Fig. 3, the emery wheel 17a is provided with the usual washers at its end faces. Said emery wheel 17a is rigidly connected to a bushing 28 by means of a nut 24 which clamps the emery wheel 17a and said washers, to a shoulder of said bushing 28. The bushing 28 is turnably mounted on a stud 15, which has a threaded shank portion 16. Longitudinal movement of the bushing 28, relative to

the stud 15, is prevented by means of the usual nut-member 25, which is mounted upon the threaded shank portion 16. The frusto-conical wall of the nut-member 25 provides sufficient bearing surface for the bushing 28, so that the bushing 28 can turn freely relative to the member 25. The shank portion 16 is screwed into a tapped bore of the arm 14a of the bracket 14.

The jaws 9 and 12 are adapted to slidably engage the vertical depending rod 3, which is connected to the frame of the mechanism.

Since the member 11 can turn freely on the pivot pin 18, the spring 20 maintains the adjacent planar upstanding walls of the jaws 9 and 12 in abutting relation, when the device is in the closed position shown in Fig. 2. The spring 23 normally keeps the peripheries of the emery wheels 17 and 17a in close or in abutting relation. Referring to Fig. 2, spring 20 urges member 8 to turn clockwise from its normal position shown in said figure, through a limited arc, until said spring 20 is under no stress. The stronger spring 23 presses a planar face of jaw 12 against the adjacent planar face of jaw 9, thus holding member 8 in the normal position shown in Fig. 2. When the handhold portions 5 and 5a are forced towards each other, the spring 20 causes the member 8 to turn through said limited arc, to the position shown in Fig. 5, before the adjacent abutting planar walls of the jaws 9 and 12 are separated from each other. Therefore the emery wheels 17 and 17a can be spaced substantially from each other, as shown in Fig. 5, before the jaws 9 and 12 are separated.

Upon further pressing the handhold 5 towards the handhold 5a, the spring 20 loses its stress and it holds member 8 against further turning movement, so that the jaw 12 is then separated from the jaw 9, while the member 8 remains substantially in the same position shown in Fig. 5.

In order to apply the jaws 9 and 12 slidably to the rod 3, the member 4 is turned clockwise from the position shown in Fig. 5, until the jaws 9 and 12 separate sufficiently to locate the rod 3 between said jaws. The spring 23 is then allowed to operate so as to force the jaw 12 towards the jaw 9. The jaw members 9 and 12 engage the rod 3, and the adjacent planar walls of said jaws abut each other, before the emery wheels 17 and 17a contact with the knife. After the planar walls of jaws 9 and 12 have thus come into abutting position and after said jaws have thus slidably engaged the rod 3, the emery wheels are allowed to contact with the knife while the member 8 is turned counterclockwise from the position shown in Fig. 5 to the position shown in Fig. 2.

The attachment can then be moved up and down on the rod 3, while the emery wheels turn around axes which are inclined to each other so as to grind the edge of the knife.

Since the emery wheels cannot touch the knife until the jaws have slidably engaged the rod 3, it is impossible to move the attachment up and down so as to grind the knife, until the concave walls of jaws 9 and 12 are in full sliding engagement with rod 3. Hence, when spring 23 is allowed to extend, and the emery wheels are moved towards the opposed faces of the knife, said wheels contact simultaneously with the knife. The attachment is then prevented from turning about the vertical axis of rod 3.

The invention generally covers arms mounted

for relative movement so that one of said arms can be moved relative to the other arm or both arms are movable relative to a common point, grinding or sharpening members connected to said arms, and jaw means movable relative to one or both of said arms. While one of the jaws (jaw 12) is rigidly connected to arm 4, the invention is now limited to said rigid connection. Likewise, the invention is not limited to the pivotal connection between the arms. Numerous other changes and omissions could be made in the preferred embodiment illustrated herein, without departing from the spirit of the invention.

The spring 20 turns the jaw member 8 only through a predetermined arc towards the other jaw member 11, when the sharpening devices are separated. A stop could be provided on pivot member 8 or the like, in order to limit the turning movement of jaw member 8.

I claim:

1. A sharpening device comprising arms mounted for movement relative to each other, sharpening members connected to said arms, jaw members mounted on said arms, said jaw members being shaped to contact slidably with an intermediate guide member, one of said jaw members being movable relative to the respective arm, said device having resilient means adapted to move said movable jaw member relative to the respective arm and towards the other jaw member through a predetermined distance, whereby said sharpening members can be moved away from each other before said jaw members are moved out of operative position.

2. A sharpening device comprising a first arm and a second arm, a pivot member turnably connecting said arms, sharpening members connected to said arms and movable in unison therewith, the first arm having a first jaw member rigid therewith, a second jaw member mounted turnably on said pivot member, a spring connected to the second arm and to the second jaw member and adapted to turn the second jaw member on said pivot through a predetermined arc and in the direction of the first jaw member, whereby the sharpening member can be separated a predetermined distance before said jaw members are moved out of relative operative positions, and said jaw members are moved out of said relative operative positions when said sharpening members are additionally separated.

3. A sharpening device comprising a first arm and a second arm, each arm having a sharpening member connected thereto, a pivot member turnably connecting said arms, jaw members mounted for turning movement about the axis of said pivot member, one of said jaw members being connected to the first arm, the other jaw member being turnable on said pivot member relative to both arms, means adapted to turn the second-mentioned jaw member towards the first jaw member through a limited predetermined arc, so that the second-mentioned jaw member turns in unison with the first-mentioned jaw member through said limited arc when the first arm is turned relative to the second arm to move said sharpening members away from each other and further turning of the first arm then turns the first-mentioned jaw member away from the second-mentioned jaw member.

ALBERT P. KOMOW.
